BATHTUB

Roy C. Troeger, Los Angeles, and James Carter
Hermann, San Marino, Calif.

Application January 7, 1936, Serial No. 57,908

7 Claims. (Cl. 4—173)

Our invention relates to a bathtub and bathtub installations. The particular type of tub is preferably made without a finished skirt on the outside, but the exposed portions have a built-in skirt 5 of tile. The portions of the tub adjacent a wall are adapted to be connected to the wall by tiling.

A characteristic feature and an object of our invention is to simplify the construction of bathtubs, making these in such a manner that it is 10 not necessary for a manufacturer to produce both what are termed right and lefthand baths. To accomplish this purpose we form the bath 15 symmetrical as to its ends and preferably the sides are parallel. The end portions of the bath project beyond the sides, and therefore as the 20 bath is symmetrical as to its longitudinal axis, it may readily be reversed in position in accordance with the location of the plumbing in the building or the particular set-up or installation of the bath 25 in the building. The bath is provided with a drain outlet, and also preferably a waste overflow at one end, and has a slope at the bottom towards the drain, but on account of the bath being symmetrical as to its ends, it may be installed in a building to more readily make connection with 30 drain pipes already installed in the building than if the bath were made of the non-symmetrical type, and moreover, with our construction an improved appearance is given in the bathroom.

35 A further characteristic feature of our invention as regards the end portions of the bath is that these are provided with a rim, the rim also extending along the sides, and such rim at the end either forms a right angle or a prolongation of the converging end portions, and where a blunt-ended bath is used would also form a right angle. Our invention also comprehends a bath having rounded ends forming each preferably a semi-circle, but in this case the tangent to the ends 40 will form a right angle.

Another characteristic of our invention is that the tangent line at the edge of the rim between the sides and the projecting ends of the rim would form an angle of about 135°, thus developing 45 a bath with parallel sides and with the point at the ends forming 90°. This construction facilitates the fitting of the bath in rightangular corners of a building or other construction.

Another characteristic feature of our invention 50 as it relates to the installation of the bath is in providing the rim with a slightly upturned outer edge which with the tiling provides a leakproof connection. For instance, the side of the bath adjacent a wall may have tiling brought down 55 and rest on the rim inside of the bead. Again, if

an apron or skirt is to be used on the exposed sides of the bath this may be formed of tiling extending downwardly from the rim with a capping piece extending partly down over the bead and the rim. In another manner of installation 5 the parallel sides of the bath readily adapt themselves to a formation of tile seats, such seats being horizontal and having an end piece extending over the bead of the rim. A convenient manner 10 of installation is to provide the seat of a triangular construction to fit in the corner of a room with the converging opposite ends of the bath having each an edge fitting against adjacent walls of a room near the corner.

Our invention is illustrated in the accompanying drawing, in which

Fig. 1 is a plan of the preferred form of the bathtub.

Fig. 2 is a perspective view of the tub of Fig. 1.

Fig. 3 is a plan on a reduced scale of a modification having the ends formed with cutoff corners.

Fig. 4 is a modification in which the ends are rounded.

Fig. 5 is a diagram illustrating various manners 25 of installing the bath of Fig. 1 in single units.

Fig. 6 is a diagram showing the various manners of installing the bath of Fig. 1 in double units.

Fig. 7 is a vertical section through the rim portion of the tub illustrating the installation of 30 wall tile.

Fig. 8 is a vertical section through the rim portion of the tub with a tile apron or skirt.

Fig. 9 is a vertical section through the rim portion of the tub and a tile seat.

In our invention in its preferred form the bath is designated by the numeral 11. This is characterized by having a peripheral rim 12 from which the main body of the bath designated at 13 extends downwardly. The rim has a horizontal portion 14 and an upturned bead 15 at the periphery, the peripheral line being indicated by the numeral 16. This peripheral line provides two side portions 17 and 18 of the bath which are preferably parallel, and as the rim is of constant thickness the body of the bath has sides which are substantially parallel except for a slope inwardly towards the bottom. The ends 19 of the bath have converging end edges on the rim designated 19 and 20 meeting at a point 21. The angle 22 40 formed by the edges 19 and 20 of the rim produces an angle of 90°. This construction also develops corners 23 at the junction of the side edges and the edges of the ends. Thus the side edges 45 and the edges of the ends form an angle 24 of 135°. 50

Adjacent the rim the bath has sharply rounded ends 30. This being similar at both ends and at the bottom of the bath, the rounded portions 31 are of an increased radius. One end of the bath only is provided with a bottom drain outlet 32, and the end corner 30 has an overflow 33 adjacent the top of the bath. The waste outlet 32 and the overflow opening 33 may be connected to the usual waste pipes, which latter would be connected to a drain in the building in the usual manner.

We prefer to form the bath without an apron or skirt depending from the rim. The bottom of the bath has the usual slope toward the drain outlet and may be of a desired contour on the inside. The inside corners 34 complementary to the angle corners 23 are slightly rounded to give a smooth interior surface to the bath. It will be understood that the inside of the bath and the rim will be enameled in the usual manner.

A characteristic therefore of the bath illustrated in Figures 1 and 2 is that it is provided with a symmetrical rim. The ends are symmetrical and similar to each other. The sides 25 are preferably parallel and as the angle 22 formed by the two end edges of the rim forms 90°, this angle end of the bath may be advantageously fitted into a rightangular corner of a room.

In the bath of Figure 3 designated by the assembly numeral 40, the sides 41 of the rim are parallel and the ends 42 have converging edges 43 and 44 and have a cutoff transverse edge 45. The edges 43 and 44 if prolonged would form an angle 46 which is 90°. This bath has a drain outlet and overflow at one end and on its interior slopes downwardly at the bottom to the outlet. It is also preferably made without an apron, the rim extending outwardly from the main body of the bath.

40. In the construction of the bath illustrated in Figure 4 and designated by the assembly numeral 50, the sides 51 are parallel and the ends form semi-circles 52. The tangent lines 53 joining a tangent 54 on the sides converge and form an angle 55 which is 90°. This bath has the drain opening and overflow at one end, the bottom sloping toward such end. This bath is also preferably made with a laterally projecting rim having a bead and without an apron or skirt.

50. In the illustrations of Figures 7, 8 and 9 showing installation of the bath where a portion is connected to a side wall, vertical tiling 60 extends upwardly from the rim and is fitted interiorly of the bead 15. This forms a watertight connection 55 of the bath with the wall, as the bead prevents overflow of any splashed water behind the wall tiles. In the construction of Figure 8 an outlet apron or skirt 61 extends downwardly from the periphery of the rim and has a coping piece 62 extending over the bead 15. In the construction 60 of Figure 9 a tile seat 63 extends horizontally from the rim and has a coping piece 64 bridging over the bead. These constructions Figures 7, 8 and 9 are merely illustrative of manners of installing the bath with a tile finish, and it will be understood that either the sides or the end portions may be built in with the wall tiles. With the apron construction on the seat, however, it is preferable that the seat be formed along 65 one of the sides of the bath.

70. One of the advantages of the bath construction as above described in which the ends are formed symmetrical, is that it is not necessary to make the baths in so-called left and rights to fit adjacent the walls of the bathroom, or to make

connection to the nearest or most convenient drain pipe installed in the building, as the bath is readily reversible in position to locate the drain outlet of the bath adjacent the fixed drain of the building.

75. In Figure 5 there are illustrated a number of instances of different installations of the bath in a building, the main walls of the building being indicated by the numeral 70, and interior partitions or closet walls by the numeral 71. In this 10 installation, for instance, the bath assembly 72 shows the two corner edges at one end of the bath and fitted in a corner of the building. The installation of 73 shows the two adjacent end edges fitted in an outwardly projecting portion of the 15 main wall forming an angle of 90°. In the installation designated at 74 one side and two end edges are fitted in an alcove of the building wall. The installation of 75 is similar except that the alcove is provided with a seat 76 adjacent one 20 side of the bath. A corner installation 77 closes in one end of the bath and one side in which there is a seat, and leaves exposed only one side and one of the end edges. In another corner installation 78 one side has a built-in seat at the 25 corner, and the two ends are built in completely, leaving exposed only one side. The installation at 79 shows one complete end and one side built in to the walls and partition of the building. The installation at 80 is similar except that it has a 30 seat along one side of the bath.

In the illustration of double bath installations shown in Figure 6, the building wall is indicated by the numeral 85 and various partitions or transverse walls by the numeral 86. The installation 35 designated 87 shows two booths spaced apart and each having a seat aligned with the inner side wall. This leaves exposed a side edge of each end and one of the sides of the bath. In the installation designated 88 the building wall has an 40 inset section and the baths have seats facing towards the inset portion of the rim. In the installation of 89 the two baths are separated by a partition and have seats on opposite sides. It will be understood that in all of the installations 45 of Figures 5 and 6 the exposed sides of the bath will preferably be finished with a tile apron or skirt.

Various changes may be made in the details 50 of construction without departing from the spirit or scope of the invention as defined by the appended claims.

We claim:

1. A bathtub having a rim with parallel sides and outwardly converging ends, both ends being 55 similar and each forming at its extreme corner an angle of 90°, the main portion of the bath below the rim being also substantially symmetrical as to its opposite end portions except one end having an outlet opening and overflow whereby the bath may be positioned symmetrically to the walls of the building to connect to the drainage pipes in the building.

2. A bathtub having a rim, the rim being 60 parallel on its sides and having outwardly converging ends forming an angle of 90° at each end, the end portions of the rim beyond the sides being symmetrical, the main portion of the bath below the rim being also substantially symmetrical 65 as to its opposite ends, and the rim at one end being adapted to form a contact fit with a rightangular corner in a room.

3. A bathtub having a rim with parallel side edges and converging end edges, the end edges at each end forming an angle of 90°, the angle 70

between a side and its adjacent end edge being 135°, the rim being in a horizontal plane, and both ends of the bath being symmetrical in regard to its transverse center whereby either end 5 of the bath may form a contact fit with an angular corner of a room.

4. A bathtub as claimed in claim 3, the portion of the bath extending downwardly below the rim having an interior curve adjacent the right- 10 angular corner, the inside portion at the ends of the bath converging downwardly and toward each other and being substantially symmetrical as to each end, the rim having a horizontal portion with an upturned bead adjacent its periph- 15 eral edge, the bead being adapted to be imbedded in a tile wall covering and a portion of the bath contacting a wall, and on an exposed portion to have a coping tile enclosing the bead.

5. A bathtub having a horizontal rim with a 20 peripheral bead, the periphery of the bath having parallel side edges and converging end edges, the converging ends being at an angle of 90°, said

bath being installed with a portion of the periphery in contact with the straight wall of a building, said wall having tiling overlapping said bead at the portion in contact with the wall.

6. A bathtub having a horizontal rim with a 5 peripheral bead, the bath having parallel sides at the rim and converging ends, the ends projecting beyond the sides and the adjacent end edges converging at 90°, both ends of the bath being symmetrical as regards the rim, the bath being 10 installed with a horizontal seat extending laterally from one side, the seat having a coping extending over the peripheral bead at one side of the bath.

7. A bathtub having a rim with parallel sides, 15 the ends having converging edge portions with a transverse end edge at right angles to the axis of the bath, the converging portions of the ends being prolonged forming an angle of 90°, two ends of the bath being symmetrical. 20
